(57) **CLAIM**

The ornamental design for a rheological probe, as shown and described.

DESCRIPTION

FIG. 1 is a perspective view of the rheological probe in accordance with our design;

FIG. 2 is a front elevation view of the rheological probe of FIG. 1;

FIG. 3 is a side elevation view of the rheological probe of FIG. 1, the opposite side being a mirror image thereof;

FIG. 4 is a rear elevation view of the rheological probe of FIG. 1;

FIG. 5 is a top view of the rheological probe of FIG. 1; and, FIG. 6 is a bottom view of the rheological probe of FIG. 1. The broken line showing of structural features is included for the purpose of illustrating non-claimed subject matter and forms no part of the claimed design.
